UNITED STATES PATENT OFFICE.

MAX BLUMENTHAL, OF CHICAGO, ILLINOIS.

DESIGN FOR AN ADVERTISING-STAND.

SPECIFICATION forming part of Design No. 26,370, dated December 1, 1896.

Application filed September 14, 1896. Serial No. 605,803. Term of patent 3 years.

To all whom it may concern:

Be it known that I, MAX BLUMENTHAL, a citizen of the United States, residing at Chicago, in the county of Cook and State of Illinois, have invented and produced a certain new and original Design for Advertising-Stands, of which the following is a specification.

My invention relates to a novel design for an advertising-stand, the object being to provide a new and ornamental device of this description.

The accompanying drawing shows my device in front elevation.

My design consists of a base comprising a central portion ornamented by a scroll or the like in relief and two end portions projecting from said base and provided with two fountains. Upon said end portions are mounted two standards carrying a cross-piece at their upper ends, at the upper portion of which a clock is represented. Said cross-piece is provided with openings in which appear the month, date, and year. Said standards are represented as being supported by two statues, which stand upon said end portions of said base and grasp said standards in their raised hands. Said standards are provided above the portions grasped by the hands of said statues with rosettes, and at the upper-

most projecting ends are provided with knobs cast in representation of pine-cones. Mounted upon the middle portion of said base is a cigar-cutter, and to the left side of the same is a receptacle for matches, and on the other side thereof an ash-receiver, and a small lamp in front of the same. Said cross-piece at the upper ends of said standards is supported by brackets cast in the shape of a scroll and extending inwardly from said standards. Pending from said scrolls are a plurality of plates provided with ornamental borders and with scrolls upon their side and top edges upon which the card or advertisement of an advertiser is engraved. Each of said plates is provided at its four corners with eyelets, through which links pass which connect the upper of said plates with the brackets supporting said cross-piece and the links connecting each of the lower plates with the plate above the same.

I claim as my invention—

The design for an advertising-stand, substantially as shown and described.

In testimony whereof I affix my signature in presence of two witnesses.

MAX BLUMENTHAL.
